UNITED STATES PATENT OFFICE

MICHAEL T. WOYTON, OF JAMAICA, NEW YORK.

MACHINE FOR GUMMING AND MOISTENING LABELS.

1,311,199.

Specification of Letters Patent. Patented July 29, 1919.

Application filed March 9, 1918. Serial No. 221,434.

To all whom it may concern:

Be it known that I, MICHAEL T. WOYTON, a citizen of the United States, residing at Jamaica, in the county of Queens and State 5 of New York, have invented certain new and useful Improvements in Machines for Gumming and Moistening Labels; and I do hereby declare the following to be a full, clear, and exact description of the invention, such 10 as will enable others skilled in the art to which it appertains to make and use the same.

This invention relates to improvements in machines for gumming or moistening labels 15 or the like and has for one of its objects the provision of a device of this character which will apply glue or moisture or the like evenly to the surface of labels, card-board, strips of leather or the like which vary in thickness without adjusting or replacing of any 20 of the parts of the machine.

Another object of this invention is the provision of a glue pan that can be readily and conveniently removed for refilling, 25 cleaning or heating without moving the machine from its support.

A further object of this invention is the provision of a feed which will carry the label or the like directly through and away 30 from the glue or moisture applying cylinder, thereby obviating the danger of the same sticking to the cylinder.

A further object of this invention is the provision of means adapted to coöperate 35 with the feed in removing the labels or the like from the machine and which will support the labels and permit the excess glue or moisture thereon to drain therefrom into the pan so that the same can be again 40 utilized.

A still further object of the invention is the provision of a machine for gumming or moistening labels of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described, and claimed.

For a complete understanding of my invention, reference is to be had to the fol-

lowing description, and accompanying drawings, in which:

Figure 1 is a plan view of a machine for gumming or moistening labels constructed in accordance with my invention, 60

Fig. 2 is a side elevation of the same,

Fig. 3 is a longitudinal sectional view illustrating the glue or moistener applying cylinder disposed partially within the moisture or glue pan, 65

Fig. 4 is a detail sectional view of a combined sprocket wheel and pinion, and

Fig. 5 is a perspective view of a drip pan adapted to be positioned on the base.

Referring in detail to the drawings the 70 numeral 1 indicates a base of any desired material and has secured thereto vertically disposed side members 2, by means of bolts or like fastening elements 3. The side members 2 are cut away as illustrated at 4 for 75 the purpose of reducing the cost of manufacturing the same by reducing the amount of material required to make the side members and also reducing the weight of the machine in entirety so that the machine may 80 be readily carried from one point to another when desired.

A pair of transversely extending rods 5 are carried by the side members 2 adjacent their rear ends for the purpose of supporting the rear end of a glue or moisture pan 6. The glue or moisture pan 6 has formed upon its side walls adjacent its front end lugs 7 that are received within notches 8 formed in the side supporting members 2 90 and which open outwardly through the front edges thereof permitting the pan to be removed from the side members when desired. The side walls of the pan 6 are reduced in height adjacent their rear ends 95 for the purpose of defining shoulders 9 that are adapted to limit the movement of the pan toward the rear end of the side members by abutting a transverse shaft 10 journaled to the side members 2 and on which is 100 mounted a moisture or glue applying cylinder 11. The cylinder 11 is secured to the shaft 10 by means of set screws or other suitable fasteners so that the same can be readily removed when desired. The shaft 105 10 is so located in respect to the pan 6 that approximately one-half of the cylinder will be disposed within the pan so that the glue or moisture contained therein may adhere to the periphery thereof.

A transverse bar 12 is secured to the upper front edges of the side members 2 and cooperates with the side members in supporting a table 13 on which labels and the like may be placed for the purpose of feeding the same into engagement with the cylinder. The bar 12 has a catch 14 of any desired construction slidably connected thereto which is adapted to be moved downwardly in engagement with the front wall of the pan 6 for the purpose of preventing the same from becoming accidentally removed or displaced from the machine. The front wall of the pan 6 being provided with a suitable handle 15 so that the pan may be readily gripped for the purpose of removing the same when desired. The table 13 is provided with a slot 16 to permit the catch 14 to be moved upwardly when desiring to free the pan so that the same can be removed from the machine. The table 13 is provided with slots 17 for the purpose of receiving set screws 18 carried by the upper edges of the side members 2, providing a construction wherein the table may be adjusted toward and from the cylinder 11 as desired.

A pair of uprights 19 are formed upon the upper edge of the side members 2 and have mounted therein a rod 20 on which is pivotally mounted hanger arms 21 that are normally disposed downwardly in an inclined plane and in the direction of the table 13. The hanger arms 21 have journaled in their lower ends a shaft 22 on which is mounted or secured a feed roller 23 constructed from rubber or any other material suitable for the purpose and which is preferably corrugated so as to readily obtain a grip upon a label or the like when moved into engagement with the same. The shaft 22 has secured to one end thereof, a pinion 24 which meshes with a pinion 25 journaled upon the rod 20. The pinion 25 has formed integrally therewith a sprocket wheel 26 over which travels a sprocket chain 27. The shaft 10 also has secured thereto a sprocket wheel 28 over which the sprocket chain 27 passes. A shaft 29 is journaled in the side members 2 in rear of the cylinders 28 and has secured thereon a plurality of relatively spaced disks 30 constructed of rubber or any other suitable material for the purpose of engaging the label or the like to feed the same off of the cylinder. The shaft 29 has secured thereto a sprocket wheel 31 which has the sprocket chain 27 passing thereover. A suitable crank handle 32 is secured to the shaft 10 for the purpose of rotating the same which will in turn drive the cylinder 11, feed roller 23 and the shaft 29 carrying the disk 30. A spring 33 is secured to one of the side members 2 and has its free end disposed over the shaft 22 for the purpose of urging the feed roller 23

downwardly in the direction of the table 13. An adjusting plate 34 is adjustably secured to one of the side members 2 and is adapted to limit the downward movement of the feeding roller and which can be so adjusted as to permit the feed roller to come in close proximity to the table without engaging the same, thereby obviating undue wear of the feed roller if it was permitted to contact with the table during the rotation thereof.

A bar 35 is secured to the rear upper end of the side members 2 and is provided with a plurality of relatively spaced sockets to receive angularly related ends of rods 36. The rods 36 are relatively spaced and are disposed between the disks 30 and have their free ends sharpened to engage circumferential grooves 37 formed in the cylinder 11 which are adapted to engage under a label or the like passing over the cylinder and prevents the same from sticking or adhering thereto.

A suitable tray 38 is located on the base 1 for the purpose of catching any glue or moisture that may drip from the machine when the pan 6 has been removed for cleaning or other purposes.

In operation, the labels or other articles are placed upon the table in close proximity to the feed roller 23 and by rotating the crank handle 32, the label is fed onto the cylinder 11 which applies the glue or moisture thereto and the label is then received by the rods 36 and fed off of the machine by the disks 30 on the shaft 29. As the label passes along the rods 36 the surplus moisture or adhesive material thereon may drip thereon into the pan 6. The rods 36 may be readily removed from the bar 35 when desired to clean the same.

While I have shown and described the preferred embodiment of my invention, it will be understood that minor changes in construction, combination and arrangement of parts may be made without departing from the spirit and scope of the invention as claimed.

Having thus described my invention, what I claim as new is:—

1. A device of the character set forth comprising a base, a pair of side members carried by said base and having notches in their forward ends, transversely extending rods carried by said side members, a tray having its rear end supported by said rods between said side members, oppositely disposed lugs formed on said tray and received within said notches, a transversely extending bar carried by the side members, a movable catch carried by said bar and adapted to engage the tray for holding the same against accidental movement, a cylinder journaled to the side members and disposed within the tray, means feeding labels into contact with the cylinder, and means receiving the

labels after coming in contact with the cylinder.

2. A device of the character set forth comprising a supporting structure, a gumming pan removably mounted on said structure, a gumming cylinder associated with said pan, a table adjustably secured to the supporting structure, a feed roller associated with the table and cylinder, a vertically movable catch carried by said structure and adapted to engage the front of the pan, said

table having a notch to permit the catch to move upwardly to free the table, and means receiving the labels after contacting with the cylinder.

15

In testimony whereof I affix my signature in presence of two witnesses.

MICHAEL T. WOYTON.
